UNITED STATES PATENT OFFICE

115,164

DESIGN FOR AN EVENING WRAP

Fannie Zucker, New York, N. Y.

Application May 3, 1939, Serial No. 84,758

Term of patent 3½ years

To all whom it may concern:

Be it known that I, Fannie Zucker, a citizen of the United States of America, residing in 20 Cabrini Boulevard, city and county of New York, and State of New York, have invented a new, original, and ornamental Design for an Evening Wrap, of which the following is a specification, reference being had to the accompanying drawing, forming part thereof.

Fig. 1 is a front perspective view of an evening wrap showing my new design.

Fig. 2 is a rear view on a reduced scale of the evening wrap as shown in Fig. 1.

I claim:

The ornamental design for an evening wrap, substantially as shown.

FANNIE ZUCKER.
